Attorney

UNITED STATES PATENT OFFICE.

JOSEPH P. RUTH, JR., OF DENVER, COLORADO.

DISCHARGE HEAD FOR GRINDING MILLS.

Application filed April 10, 1923. Serial No. 631,114.

To all whom it may concern:

Be it known that I, JOSEPH P. RUTH, Jr., a citizen of the United States, and resident of the city and county of Denver, State of Colorado, have invented certain new and useful Improvements in Discharge Heads for Grinding Mills; and I do declare the following to be a full, clear, and exact description of the invention, such as will enable others skilled in the art to which it appertains to make and use the same, reference being had to the accompanying drawings, which form a part of this specification.

The object of this invention is to provide a novel and highly serviceable construction of discharge head for grinding mills of the class generally known as rod mills, which will permit ready discharge of properly prepared pulp, prevent pulp from splashing out, retain the rods or other grinding media, and permit ready inspection of the interior when desired.

Briefly, the invention comprises a frusto-conical head for a mill having a journal which is hollow for discharge of pulp therethrough and has a discharge flange. The journal is provided with a hollow liner secured therein, and at the inner end of the journal liner a baffle or guard plate is positioned for discharge of pulp between the plate and the liner. The plate is preferably apertured at its middle but the opening therein has a smaller diameter than the diameter of the discharge opening through said journal liner. Thus the baffle plate retains rods which may be introduced through said opening and also intercepts splash. If desired a cap may be provided to cover said opening thus making the plate solid in effect during operation of the mill.

In the accompanying drawings, wherein certain embodiments of the invention are disclosed by way of illustration,

Fig. 1 is a vertical section through the end of a mill equipped with the present discharge head;

Fig. 2 is a face view from the outer side of the baffle plate;

Fig. 3 is an edge elevation of said plate with a portion broken away;

Fig. 4 is an edge elevation of the liner for the frusto-conical portion of the head with a part broken away;

Fig. 5 is a sectional detail showing a

closure cap on the baffle plate, Fig. 6 showing a modified form of such cap.

The shell 10 of a mill having liners 12 carries a flange 14 or the like to which a frusto-conical head 15 is bolted as shown. Head 15 has an integral hollow journal 16 which rotates in bearings 17 mounted on a base B or the like. The frusto-conical portion 15 of the head has a ring liner 18 bolted thereto, and the hollow journal 16 has therein a snugly fitting more or less cylindrical liner 20 through which the pulp is discharged from the mill, this liner 20 being secured as by means of set screws 22. By loosening screws 22 liner 20 may be readily removed from the journal 16 for easy access to the interior of the mill.

A baffle plate or guard plate 24, which may be frusto-conical as shown, is mounted upon the inner end of the liner 20 and is there retained by bolts 25. Webs or blades 26 carried by plate 24 serve to space the plate from the end of the journal liner 20 and provide between them passages or channels 27 for the upward flow of pulp between the plate 24 and liner 20 so that the pulp may overflow the annular discharge lip 28 which constitutes the discharge opening of the mill and is defined by an annular flange on liner 20 in which flange the bolts 25 are mounted for retention of plate 24. Baffle plate 24 has a central opening 30 defined by an annular flange 31, and the blades 26 may terminate short of the flange 31 so as to insure free discharge of pulp, as indicated at 29. Opening 30 permits the insertion of rods into the mill and inspection of the mill, the plate 24 insuring retention of the rods and intercepting splash. The diameter of the baffle plate 24 is greater than that of the discharge opening 28 so as to cause the pulp being discharged to flow at least partially from points below the pulp level indicated by line a, the said diameter of plate 24 being sufficiently less than the internal diameter of journal 16 to permit baffle plate 24 to be removed with the journal liner 20. The channels 27 are alined with short channels 32 in the ring liner 18.

To the outer end of the journal 16 there is bolted a discharge flange 35 as seen at 36, over which the pulp flows as it leaves the liner 20. Flange 35 preferably is frusto-conical as shown and has its base provided with

an exterior annular flange or rim 38 which serves to intercept any pulp which runs down the outer face of the discharge flange 35 as such pulp which clings to the lip of flange 35 is carried upward during rotation of the mill. In this manner the rim 38 keeps the pulp out of the bearings at 17 and insures long life thereof.

If it is desired to close the end of the mill entirely during operation, a cap 40 may be provided for placing over the opening 30 of the baffle plate. Thus any probability of splashing of pulp from the mill will be prevented. This cap 40 may have an annular friction flange 42 for engaging the inner wall of the part 31 to retain the cap, as in Fig. 5, or it may be secured to the plate 24 by means of machine screws as seen in Fig. 6. In both instances the cap 40 may be provided with a handle 44.

In operation the pulp level indicated by line *a* will be determined by the discharge opening 28 in journal liner 20, the pulp flowing from the interior of the mill through the channels 32 in ring liner 18 and channels 27 between baffle plate 24 and the end of liner 20. When the cap 40 is removed, rods may be introduced through opening 30 into the mill and the interior may be inspected. The frusto-conical form of the baffle plate 24 will insure return of the rods into the mill should they work outward during the tumbling movement thereof. By loosening the set screws 22, the liner 20 and baffle plate 24 may be removed for access to the interior of the mill and removal of rods therefrom.

I claim:

1. In a grinding mill, a head having a journal, a liner for said journal and a baffle plate secured on the inner end of the liner, the liner and plate being removable together from said journal at its outer end.

2. In a grinding mill, a head having a hollow journal, a liner in said journal and removable therefrom, and a baffle plate secured on the inner end of said liner and spaced slightly therewith axially of the mill.

3. In a grinding mill, a head having a hollow journal, a liner in said journal, the head having a frusto-conical portion connecting the journal with the mill, and a

frusto-conical baffle plate secured to the inner end of the liner and removable from the mill with the liner.

4. In a grinding mill, a head having a 55 hollow journal, a liner in said journal whose smallest internal diameter determines the discharge opening from the mill, and a baffle plate secured to the inner end of the liner and spaced therefrom, the diameter of the 60 plate being greater than the diameter of the discharge opening.

5. In a grinding mill, a discharge head having a hollow journal, a liner removably mounted in said journal, the smallest internal diameter of the liner determining the discharge opening from the mill, and a baffle plate secured to the inner end of the liner and spaced therefrom, the diameter of the 65 plate being greater than that of the discharge opening and less than that of the interior of the journal, whereby the baffle plate 70 may be removed with the liner.

6. In a grinding mill, a discharge head having a hollow journal, a liner in said journal whose smallest internal diameter determines the discharge opening from the mill, and a baffle plate secured on the inner end 75 of the liner having a diameter greater than that of the opening and having an opening 80 at its center of smaller diameter than the discharge opening, said plate being removable with the liner from the outer end of the journal.

7. In a grinding mill, a discharge head 85 having a frusto-conical portion and a journal extending from said portion, the journal being hollow, a liner for said frusto-conical portion, a liner in said journal having a discharge opening therethrough, and 90 a baffle plate secured to the inner end of the liner and spaced therefrom, the plate having a diameter greater than that of said opening and extending toward the center over at least a portion of said opening, channels being provided between the plate and the end of the journal liner for the passage of pulp, the liner for the frusto-conical portion of the 95 head having passages therein aligned with the channels.

In testimony whereof I affix my signature.
JOS. P. RUTH, JR.
